UNITED STATES PATENT OFFICE.

AMANDUS HOWELL RANDOLPH, OF CORRY, PENNSYLVANIA.

DUMPING-WAGON.

SPECIFICATION forming part of Letters Patent No. 739,715, dated September 22, 1903.
Application filed March 28, 1903. Serial No. 150,018. (No model.)

To all whom it may concern:

Be it known that I, AMANDUS HOWELL RANDOLPH, a citizen of the United States, residing at Corry, in the county of Erie and State of Pennsylvania, have invented a new and useful Dumping-Wagon, of which the following is a specification.

My invention is an improvement in dumping apparatus, and while it is shown as applied to a wagon it is equally as well adapted for use with cars.

The object of the invention is to provide a double pivoted bottom and means for dumping the same, whereby the material may be dumped in the center of the road or track or at the sides of same.

My invention consists in a sectional bottom, the sections extending the length of the car or wagon and so pivoted at their ends that each section can be tipped in either direction.

The invention consists also in the special features of construction pointed out in the claims and shown in the accompanying drawings, in which—

Figure 1 is a side view of a wagon equipped with my dumping apparatus. Fig. 2 is a plan view of Fig. 1. Fig. 3 is an end view showing the dumping mechanism. Fig. 4 is a section about the line 4-4 of Fig. 2. Fig. 5 is a detail view, partly in section, showing the bearing-plates. Fig. 6 is a perspective view showing from the under side an end of one of the sections and the bracket by which it is secured to a revoluble shaft running the length of the vehicle.

In the drawings, A represents the sides of the body of a wheeled vehicle, the ends A' of which preferably extend below the sides. Arranged centrally in the lower part of the body and extending from end to end is a vertically-arranged strip B, diamond-shaped in cross-section. Journaled in and extending through the end pieces and below the plane of the bottom of the body are two parallel shafts C, each arranged midway between one of the sides and the strip B. Adjacent the inner faces of the ends a bracket D is rigidly secured on each shaft, having arms D' extending laterally and slightly upwardly. The two bottom sections E are supported by and secured to these brackets and have bevel-

led side edges, as shown at E'. On each end of each shaft are rigidly mounted gear-wheels F. On the outer and inner faces of each end piece between the gears F are arranged metal plates F', and journaled in these plates are gears F² of similar size and larger than the gears F. Each set of gears F² mesh together and also with the adjacent gear F. On one of the end pieces is mounted a quadrant F³, above and meshing with one of the gears F². A lever F⁴ is rigidly secured to the quadrant and slides between parallel segments F⁵, bolted together but spaced apart, and a gripping-catch F⁶ is pivoted to the lever and engages notches cut into the outer segment.

The operation of my device is as follows: When it is desired to dump the material to one side, the lever, which is normally in a vertical position, is moved to the left, the gears and shafts are rotated, and the outer edges of the bottom sections are swung downward in the direction of the lower arrows of Fig. 4. If, however, it is desired to dump the material on the road or track, the lever is moved to the right and the inner edges of the sections swing downward, the outer edge rising, as indicated by the upper arrows of Fig. 4. The positions occupied by the bottom sections when the lever is moved in each direction are shown in dotted lines in Fig. 4.

It will be noted that when in its normal position the center of each section E is slightly lower than the sides.

Having thus fully described my invention, what I claim as new, and desire to secure by Letters Patent, is—

1. A dumping apparatus comprising two parallel bottom sections pivoted centrally adjacent each end, and means common to each section for tipping them toward or away from each other.

2. The combination with a vehicle, of parallel shafts revolubly journaled in the ends of the vehicle, brackets secured on said shafts, a stationary strip running from end to end of the vehicle between the shafts, a bottom section carried by the brackets on each shaft, and means for rotating the shaft in either direction.

3. The combination with a vehicle, a strip extending centrally from end to end of the

vehicle, shafts journaled in the ends on each side of the stationary strip, and extending through said ends, bottom sections rigidly connected to and supported by said shafts, 5 said sections extending when in a normal position from the stationary strip to the sides of the vehicle, gears at each end of each shaft, intermediate gears at each end intermeshing

and each meshing with a gear on one of the shafts, a quadrant engaging one of the intermediate gears, and a lever adapted to move said quadrant in either direction.

AMANDUS HOWELL RANDOLPH.
